UNITED STATES PATENT OFFICE.

CALVIN H. FITCH, OF MIDDLETOWN SPRINGS, VERMONT.

BED-BOTTOM.

SPECIFICATION forming part of Letters Patent No. 252,654, dated January 24, 1882.

Application filed November 25, 1881. (No model.)

To all whom it may concern:

Be it known that I, CALVIN H. FITCH, a citizen of the United States, residing at Middle-
5 town Springs, in the county of Rutland and State of Vermont, have invented certain new and useful Improvements in Bed-Bottoms; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 This invention is in the nature of improvements in that class of bed-bottoms in which the bottom proper is made of inelastic but flexible material which is made to yield under the weight of the occupant by means of spring supports therefor.

In these improvements the bottom proper is made up of crossed strips of sheet metal rigidly united at their points of intersection. The bottom so formed is adapted to be hooked on 25 springs secured to cross-bars arranged at the ends of the bottom, which bars are adapted to be firmly connected to side rails either of the bed or forming part of the bed-bottom as an article of manufacture. These cross pieces or 30 bars, besides serving to support the bottom proper, are so constructed with reference to their fastening means as to afford a variable-tension device for taking up the slack and keeping taut the bed-bottom. The fastening means 35 referred to are socket-pieces at each end of the cross-bars, adapted to straddle the side rails without mortising or otherwise cutting said rails, and held on said side rails at such an adjustment as to keep the bed-bottom taut by 40 means of one of several headed pins, screws, or devices for each socket-piece, and screw-bolts, the said headed pins in the act of applying the last cross-piece serving as fulcra against which the bar is depressed like a lever and 45 draws the bed-bottom taut.

In the accompanying drawings, in the several figures of which like parts are similarly designated, Figure 1 is a perspective view of my improvements in position for application to 50 a bedstead, the cross-piece and a part of the bottom at one corner being broken away to show the socket. Fig. 2 is a side elevation

with one cross-piece bolted to the side rails and the other cross piece in position for straining or drawing taut the bottom. Fig. 3 is a perspective view of one of the sockets, and Fig. 4 is a cross-section on line *x* *x* of Fig. 1, Figs. 3 and 4 being on the same enlarged scale; Figs. 5 and 6, side and top views, respectively, of a modification of the socket. 55 6c

The letter *A* designates a preferred form of bed-bottom proper. This bottom is composed respectively of longitudinal and transverse strips *a* *b* of sheet metal—say, brass—which are united rigidly at all of their intersecting 65 points by means of rivets *c*, so as to make a firm, preferably inelastic, but flexible bottom.

I do not limit my invention to the use of any particular form or construction of bottom, but may use the bottom described—woven-wire, 70 canvas, or other material.

The bottom is secured to the hook-shaped ends of springs *d*; and I prefer, for economy and strength, twin springs, as shown in the drawings. The bottom will be best retained in place 75 upon the hooked ends of the spring *d* by superposing strips *e*, made separate from the bottom. These springs are secured to bars *f*, which form the head and foot bars of the bed. The bars *f* are provided at their ends with vertically depending socket-pieces *B*. Referring to 80 Figs. 3 and 4, each of these sockets has a horizontal lip, *g*, through holes in which fastening devices are passed into the under side of the bar. At right angles to this lip are two parallel plates, *h* *i*, connected on top by a cross-plate, *j*, which latter is slotted longitudinally at *k*. The plates *h* and *i* are perforated at their lower ends, and the plate *i* is thickened, so that its perforation *l* may be screw-threaded, the 85 said perforations serving to receive a screw or bolt, *m*, whose thread engages with the threaded hole *l* in the plate *i*, said plate thus serving the purpose of a nut for the bolt, and thereby dispensing with an independent or loose nut. 90 A loose nut may, however, be employed. The 95 sockets constructed as described may be cast in one piece of metal, not altogether inelastic, to permit the plates *h* and *i* to be drawn toward each other by the screw, and yet sufficiently rigid to retain their shape. 100

Rails *n*, which may form part of the bed-bottom as put up for sale, or which may be the side rails of a bedstead, have on their up-

per edge at each end a plurality of headed devices, *o*, set apart at a suitable distance. These devices may be screws. The bars *f* form the cross-pieces to connect these rails, and their 5 sockets straddle said rails, and their adjacent edges abut against one of the devices *o* at each end of each rail to hold the bars at the proper adjustment upon the rails, while the bolts *m*, passed through the plates *h i* beneath 10 the rails, lock the bars *f* down upon the rails, and thereby hold the bottom in position. The unused devices *o* project through the slots *k* of the plate *j*.

The bottom *A* having been secured to the 15 hooked springs of one bar, and that bar having been applied to the rails, as described, the other end of the bottom is likewise hooked to the springs of the other bar. This other bar is then brought into position on the rails, the 20 sag of the bottom indicating at which devices *o* the sockets shall be applied, and such sockets being applied to said devices, as indicated at the right-hand end of Fig. 2, said devices become fulera, and the sockets, with their cross- 25 bar, become levers, upon the depression of which levers the bottom is drawn taut, and the bolts *m* being applied, the bottom is secured in its taut state. When by usage the bottom again sags the bolts of one cross-bar are 30 moved, the sockets placed against others of the devices *o*, and leverage used to draw the bottom taut again. Thus the sockets, operating against the devices *o*, become tension devices for the bottom, and the tension can be 35 easily and economically regulated. The devices *o* prevent longitudinal movement or approach of the sockets, and the bolts *m* prevent vertical displacement. The devices *o* are driven directly into or secured upon the side rails with- 40 out marring or weakening them. So also the sockets are applied and used without recessing or mortising.

Even in cast metal—as, for instance, malleable castings—there is sufficient resilience to admit of the plates *h i* of my sockets being drawn 45 toward each other by the screws or bolts *m* to clamp the sockets to the rails or cause the said plates to bind upon the faces of the rails.

In Figs. 5 and 6 the socket *B'* is secured to 50 the side rail by two bolts passed through the rail. In this form of socket one bolt will take the place of the headed pin. This form of socket may be made adjustable by having a plurality of bolt-holes for each bolt.

55 What I claim is—

1. The bed-bottom *A*, composed solely of crossed strips of sheet metal united at their

intersections by suitable fastenings, so as to be securely held together and adapted to be hooked to springs to support the same at its 60 ends only, substantially as described.

2. In a bed-bottom, the combination of a bottom proper, spring-hooks to engage and support such bottom at its ends only, end cross-bars to which such spring-hooks are secured, 65 sockets at the ends of such cross-bars, and a framing to which such sockets are bolted to sustain the whole, substantially as described.

3. The cross-bars of a bed-bottom, provided with sockets, combined with the side rails, 70 abutments thereupon against which the sockets rest, and bolts to lock said sockets and cross-bars upon the rails, substantially as described.

4. The cross-bars of a bed-bottom, adapted 75 to receive the bottom proper, combined with sockets on said cross-bars, the side rails, a plurality of headed pins or their described equivalents arranged upon said rails, and bolts to secure the said sockets in place upon the 80 rails, said pins serving as fulera for the sockets, which, in applying the bottom to the rails, are used as tension devices to take up the sag of the bottom, substantially as described.

5. The cross-bars of a bed-bottom, provided 85 with sockets to secure them to the side rails, said sockets having side plates to clasp the rails, and slotted connecting-plates, combined with a plurality of abutments on the rails, whereby the adjustment of the cross-bars necessary to take up the sag of the bottom is secured, substantially as described.

6. The cross-bars and a bed-bottom secured thereto, combined with side rails, sockets on 90 said cross-bars to connect the bars and rails, abutments on said rails to effect the adjustment and holding of the cross-bars longitudinally of the rails, and bolts to lock said sockets to the rails and prevent vertical displacement, substantially as described.

100 7. The cross-bars to support the bottom of a bed, provided with sockets adapted to straddle the rails, and adjustably secured to said rails by means of superficial abutments on the upper faces of such rails, and bolts engaging such 105 sockets and bearing against the bottoms of such rails, substantially as described.

In testimony whereof I affix my signature in presence of two witnesses.

CALVIN H. FITCH.
